UNITED STATES PATENT OFFICE.

CHARLES ITSCHNER, OF CHICAGO, ILLINOIS, ASSIGNOR OF ONE-HALF TO FRANKLIN P. SMITH, OF CHICAGO, ILLINOIS.

STAIRWAY.

1,291,904.

Specification of Letters Patent. Patented Jan. 21, 1919.

Application filed May 10, 1917. Serial No. 167,639.

To all whom it may concern:

Be it known that I, CHARLES ITSCHNER, a citizen of the United States, and a resident of Chicago, county of Cook, and State of Illinois, have invented certain new and useful Improvements in Stairways, of which the following is declared to be a full, clear, and exact description.

This invention relates to stairways, and 10 its principal object is to provide a stairway of simple, substantial and fire proof construction. Another object is to provide a combined metal and concrete stairway, the metal portion of which may be assembled at 15 the factory and erected at the building where it is to be used. Another object is to provide a stairway with a flat soffit which forms part of the vertical members of the stairway. With these and other advantages 20 in view, this invention consists in the several novel features hereinafter set forth and claimed.

The invention is clearly illustrated in the accompanying drawings, in which:

25 Figure 1, is a vertical, longitudinal section through a fragment of a stairway, landing and post, embodying the preferred form of the invention; Fig. 2, is a cross section taken on line 2—2 of Fig. 1; and Fig. 3, is 30 a vertical, longitudinal section of a fragment of the metal parts of the stairway.

Referring to said drawings, the reference 35 character 8, designates a landing place or floor of a building, from which runs a flight of stairs having the usual balustrade (not shown). In its preferred form, the stairs comprise a flat sheet metal soffit 11, having upwardly bent side portions that form the stringers 12, 13. For obtaining greater 40 strength, the upper edges of the stringers are bent outward to provide flanges 14, 15, to one of which the balusters may be secured.

Conveniently the soffit 11, may be made of 45 two metal sheets, running lengthwise from top to bottom of the stairway, and secured together by a T-iron bar 16, riveted or otherwise fastened thereto. Obviously the vertical web of the T-iron bar stiffens the structure, and additional reinforcement rods 17, 50 run lengthwise of the soffit, and are em-

bedded in the concrete filler, as will appear presently.

The risers 18, are preferably made of sheet metal, although not necessarily so, and each is formed with the usual nosing 19, at the 55 top and with flanged upper and lower edges, the flanges 20, being flush with the tread 22, of one step and the flange 21, being flush with the tread of the next step therebelow. The risers are secured to the stringers by 60 angle iron brackets 24, bolted or riveted to the ends of the risers and sides of the stringers. Conveniently stay rods 23, connect the upper portions of the risers with the soffit to hold the risers in place before the concrete is filled in.

The concrete filler is shown in Figs. 1 and 2, and between the opposing flanges 20, 21, it is leveled off to provide the treads 22. A strip 25, is secured to the underside of the 70 soffit at the side adjacent the wall 26, of the building, and closes the space between the soffit and wall.

More or less variation of the exact details of construction is possible without departing 75 from the spirit of this invention; I desire, therefore, not to limit myself to the exact forms of the construction shown and described, but intend in the following claims to point out all of the invention disclosed 80 herein.

I claim as new, and desire to secure by Letters Patent:

1. In a stairway, a flat sheet metal soffit, having upturned stringers formed integral 85 therewith, sheet metal risers secured to said stringers, the lower edges of said risers being spaced from said soffit, lengthwise extending reinforcement rods between said soffit and risers, and a concrete filler. 90

2. In a stairway, a flat sheet metal soffit having upturned stringers formed integral therewith, said stringers being formed with out-turned flanges at their upper edges, metal risers secured to said stringers, the 95 lower edges of said risers being spaced from said soffit, lengthwise extending metal reinforcement rods between said soffit and risers, and a concrete filler.

3. In a stairway, a flat sheet metal soffit 100

having upturned stringers formed integral therewith, risers secured to said stringers and formed with top and bottom flanges projecting in opposite directions flush with 5 two treads.

4. In a stairway, a flat sheet metal soffit, composed of two sheets united at the mid-

dle of the stairway by a T-iron bar, and having integral upturned stringers, metal risers secured to said stringers, lengthwise 10 extending reinforcement rods between the soffit and risers, and a concrete filler.

CHAS. ITSCHNER.
